UNITED STATES PATENT OFFICE.

ALBERT F. COLLINS, OF MINNEAPOLIS, MINNESOTA.

BANK CHECK.

1,407,256.

Specification of Letters Patent. Patented Feb. 21, 1922.

Application filed September 12, 1919. Serial No. 323,396.

To all whom it may concern:

Be it known that I, ALBERT F. COLLINS, a citizen of the United States, residing at Minneapolis, in the county of Hennepin and 5 State of Minnesota, have invented new and useful Improvements in Bank Checks, of which the following is a specification.

My invention relates to improvements in bank checks, money orders, drafts, notes and 10 like instruments. The term "check" appearing herein will, therefore, be assumed to include the above and similar instruments.

Heretofore, checks have been marked with letters, figures or characters by "check protectors" to prevent the alteration thereof and checks have been used bearing tables 15 of figures, certain of said figures being punched out to prevent alterations. These checks have been more or less successful, 20 but the checks which are marked or imprinted with words, figures or characters require so much time in preparation and handling as to greatly limit their use. This disadvantage is also present in checks from which 25 figures are punched to indicate the amounts thereof and such checks have often been raised by skillful hands.

It is the object of my present invention to provide a check adapted to be quickly and 30 easily marked to indicate the amount to be paid and so constructed as to prevent the raising thereof.

A further object is to provide a check of this kind, which not only saves the time of 35 persons marking such checks for protection, but saves the time of persons signing the checks and also the time of paying tellers or others handling the same.

More specifically it is my object to provide 40 a check having columns of figures thereon indicating, respectively, dollars, tens of dollars and so on in decimal progressive order, said columns of figures being located between tinted zones, and a series 45 of perforations in each column of figures, each series including oblique perforations which cancel the figures representing amounts higher than that for which the check is drawn, a horizontal perforation cutting 50 out the figure representing the next lower amount and an indicating perforation in the adjacent tinted zone which together with said horizontal perforation readily directs the vision to the figure representing the amount of the check.

A further object is to provide a check hav-

ing a series of columns of such figures located between tinted zones, said figures being arranged above the written indication of the amount of the check, whereby comparison between the marking perforations in 60 said columns of figures and said written indication may be quickly made by the persons signing, paying or otherwise handling 65 the check.

A further object is to provide a check of this kind having a space in which the amount of the check is indicated for the convenience of the person perforating the same, said space being located near the center of the check and at a point observable, 70 when one end thereof is inserted in a perforating device.

In the accompanying drawings, Fig. 1 is a view representing my improved check in 75 the blank; Fig. 2 is a perspective view of my check in position within a perforating machine preparatory to being punched and clearly shows the utility of the central writer 80 indication of the amount for which the check is drawn; Fig. 3 is a view of the completed check; Fig. 4 is a fragmentary perspective view of a device for perforating the check and Figs. 5 and 6 are perspective views in detail of the dies therein.

Referring to the accompanying drawings, I have used the reference numeral 10 to designate the body of the check. In the upper right hand corner of the check are usual lines or spaces 11 and 12 in which the 90 number of the check and the date thereof may be placed. Near the bottom of the check is a longitudinal tinted or otherwise marked zone 13 for the payee's name and in line therewith and at the right extremity of the body 10 is a tinted zone 14 to receive written figures designating the amount 95 of the check. Beneath said zones 13 and 14 is a similar zone 15 for the drawers' signature. Beneath the number and date lines 11 and 12 and above the zones 13 and 14 is a table of figures comprising a number of 100 columns of figures, each increasing progressively from bottom to top, said columns representing from right to left, decimal 105 increasing amounts. Thus, the column on the right indicates dollars, one to nine inclusive, the next column represents tens of dollars, ten to ninety inclusive, and so on, the highest amount shown being nine thousand. Any number of columns of figures desired may, of course, be employed. A tint-

ed or otherwise protected zone 16 extends above said column of figures and on each side of each column. Peculiar perforations are formed in the check to cancel the figures 5 in said columns indicating amounts higher than those of the check, also to cancel the figures indicating the next lower amounts and further to cut guides in the tinted zones adjacent said columns of figures to direct 10 the sight to the undisturbed figures representing the amount of the check. I employ a similar series of perforations for each column of figures, including several parallel oblique perforations 17 arranged between upper and lower triangular perforations 18 (Fig. 3). In addition to these angular perforations is a horizontal perforation 19 which is spaced beneath said lower triangular perforation 18 at a distance equal 15 to the space occupied by each figure, and in the adjacent tinted zone, on a line midway between the lower triangular perforation 18 and said horizontal perforation 19 is an arrow-head or guide perforation 20. 20 The oblique and triangular perforations 17 and 18 cut the check in such a manner that no complete figure, greater in amount than that of the check, can be read. The figure in each column, representing the amount to be paid stands out clearly in the space left 25 between the lower triangular perforation 18 and the horizontal perforation 19. The guide perforation 20, opposite said space, and said horizontal perforation 20, which 30 resembles an underscore, readily draws attention to the payable amount appearing in said space. It will be noted that this combination of angular and horizontal perforations, together with the guide perforation in 35 the tinted zone minimizes to a great degree the possibility of altering the check.

In raising the instrument, the horizontal perforation would fall in position formerly occupied by an angular perforation and the 40 guide perforation 20 would necessarily occupy a new position, thus necessitating the plugging of the original perforation in the tinted zone. The task of plugging the series 45 of perforations and recutting the same in the patched sections would be difficult and quite impossible without detection.

I prefer to perforate the blank check by means of a punching device which simultaneously perforates all of the columns of 50 figures in the check. The particular mechanism of this device is pointed out in a companion application for patent to be filed herewith. Parts of said device are however, illustrated herein to better explain the 55 functions of certain features of my improved check. Fig. 2 of the drawings is a perspective view of my improved punching device. The base 21 and cover 22 contain the punching mechanism. A guide 23 in the cover 60 22 receives my check, which is provided with

a tinted zone 10^a wherein are placed the written figures indicating the amount thereof. This zone, being placed near the center of the check, is plainly visible to the operator of the device, who shifts the levers 24 to desired positions with respect to the indicator 25, preparatory to depressing the handle 26. Referring to Fig. 4, the guide 23 passes through a series of die carriages 27, one of which is shown. These carriages are connected with the levers 24, each carriage supporting thereon a fixed die 28 and a vertically slideable die 29, the latter being connected by means of a pintle 30 with an equalizing bar 31. A rod 32 oscillated by the hand lever 26 is connected through links 33 and 34 with a push rod 35, which slidably bears upon the equalizing bars 31. A check placed within the guide 23, rests between the dies and depression of the handle 26 causes said check to be perforated, in accordance with the adjustment of the levers 24. The die members 29 have projections 36 and 37 for cutting the perforations 17 and 18 in my check and projections 38 and 39 for cutting the perforations 19 and 20 therein.

The following words of instruction appear upon the face of the check: "Pay no more in dollars than amount indicated by arrow head." These checks, of course, may be drawn for amounts including cents, but the table of figures employed has reference to dollars only.

In summarizing the advantages of my check, it will be remembered that the amount of the check written near the center thereof facilitates in perforating the check; the oblique perforations 17 and 18 in the columns of figures effectually obliterate all higher amounts than those to be paid; the arrow head perforations 20 in the tinted zones point to the amounts to be paid; the horizontal perforations 19 serve further to prevent alteration and together with the arrow head perforations quickly draw the vision to the proper amounts payable; the location of the table of figures above the written indication of the amount of the check and the signature line renders rapid comparison between the perforated markings and said written indication; the perforations in the right end of the check insures the placing of indorsements in proper position; and the absence of imprinted lines upon the checks minimizes the folding and crumpling thereof in handling.

Having described my invention, what I claim as new and desire to protect by Letters Patent is:

1. A check having thereon a plurality of spaced columns of figures, the figures in each column increasing progressively from the bottom to the top thereof, tinted zones adjacent to said columns of figures and

series of perforations in the check, one series being cut in each column of figures and including a vertical group of oblique perforations, a lateral oblong perforation spaced 5 beneath said group and an indicating perforation in the adjacent tinted zone opposite the space above said oblong perforation.

2. The combination of a check having thereon a plurality of spaced columns of 10 figures, the figures in each column increasing progressively from the bottom to the top thereof, tinted zones near said columns of figures, cancelling perforations in said columns of figures cutting out amounts other 15 than those to be paid and indicating perforations in said tinted zones designating the amounts payable.

3. A check of the class described having a space for signature, a space for the writing 20 indication of the amount of the check,

columns of figures, tinted zones adjacent thereto, said figures and zones being located above said spaces, cancelling perforations cutting said columns of figures above and below the amounts to be paid and offset indicating perforations cutting the tinted 25 zones.

4. A check bearing a plurality of spaced columns of figures and having a tinted protective zone on one side of each column, 30 cancelling perforations cutting said columns of figures and offset indicating perforations cutting said zones, said perforations indicating the amount of the check and preventing alterations thereof. 35

Signed at Minneapolis, in the county of Hennepin and State of Minnesota, this 5th day of September, 1919.

ALBERT F. COLLINS.
